CLAIM

The ornamental design for a vehicle center display, as shown and described.

DESCRIPTION

FIG. 1 is a front elevational view of a vehicle center display, showing our new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a top, front and left side perspective view thereof; and,
FIG. 7 is a top, rear and left side perspective view thereof. The de-emphasized and half-toned portions of the vehicle center display circumscribed by the broken lines illustrate the environmental structure and form no part of the claimed design and the broken lines form an unclaimed boundary.
